UNITED STATES PATENT OFFICE.

ADELBERT C. HIMEBAUGH, OF BURR OAK, MICHIGAN.

STEERING-SLED.

1,104,799.

Specification of Letters Patent. Patented July 28, 1914.

Application filed February 13, 1913. Serial No. 748,144.

To all whom it may concern:

Be it known that I, ADELBERT C. HIMEBAUGH, a citizen of the United States, residing at Burr Oak, Michigan, have invented 5 certain new and useful Improvements in Steering-Sleds, of which the following is a specification.

This invention relates to improvements in steering sleds.

10 The main objects of this invention are: First, to provide an improved steering sled in which the steering is effected by laterally flexing the runners, and one in which the runners are effectively supported and at the 15 same time, are very easily flexed. Second, to provide an improved sled having these advantages which is comparatively simple and economical in structure and at the same time which is very durable and very easily operated.

Further objects, and objects relating to structural details, will definitely appear from the detailed description to follow.

I accomplish the objects of my invention 25 by the devices and means described in the following specification.

The invention is clearly defined and pointed out in the claims.

A structure which is a preferred embodiment of my invention is clearly illustrated 30 in the accompanying drawing forming a part of this specification, in which:

Figure I is a perspective view of a structure embodying the features of my invention. 35 Fig. II is a plan view of the structure shown in Fig. I, the runners being shown in one of their flexed positions by dotted lines. Fig. III is an inverted view, the runners being shown in flexed positions by dotted lines.

40 Fig. IV is a vertical transverse section on a line corresponding to line 4—4 of Fig. II. Fig. V is a detail vertical longitudinal section on a line corresponding to line 5—5 of Fig. II. Fig. VI is an enlarged detail section on a line corresponding to line 6—6 of Fig. IV. Fig. VII is an enlarged detail section on a line corresponding to line 7—7 of Fig. II. Fig. VIII is a detail horizontal section on a line corresponding to line 8—8 50 of Fig. V. Fig. IX is a detail vertical section on a line corresponding to line 9—9 of Fig. III, showing by dotted lines, one of the flexed positions of the side member of the knee. Fig. X is a perspective view of a 55 slightly modified structure, the structure

here illustrated being a two-knee structure.

In the drawing similar reference characters refer to similar parts throughout the several views, and the sectional views are taken looking in the direction of the little 60 arrows at the ends of the section lines.

Referring to the drawing, the runners 1 are preferably formed of T-shaped steel. Any suitable material may be used which permits the runners being sprung or flexed 65 laterally.

The body or top 2 in the structure illustrated is merely a flat board having a forwardly projecting arm 3 at its forward end.

The knees 4 are formed of metal and are 70 provided with top pieces 5 turned downwardly at their outer ends into braces 6 which lap upon and are secured to the side members of the knees.

The construction shown in Fig. I is provided with three knees, the rear and central knees being rigidly secured to the body as by bolts 7 or suitable rivets. The front knee is slidably associated with the body, it being 75 preferably connected thereto by the centrally disposed clip 8 so that the knee may be disposed longitudinally below the body.

The raves are formed of sections 9, 10 and 11, the rear rave sections being rigidly secured to the rear and central knees by means 85 of the rivets 12. The sections 10 are pivotally secured to the forward ends of the sections 9 by the pivots 13. These pivots are located in front of but adjacent to the central of first rigid knee, that is, the first knee 90 which is rigidly secured to the body.

The forward rave sections 11 are secured by pivots 13 to the forward ends of the sections 10, these pivots being disposed in front of but adjacent to the front or swinging 95 knee. The front ends of the rave sections 11 are secured to the front ends of the runners and the front ends of the runners and raves are connected by the cross bar 14. Mounted in this cross bar by means of the pivot 15, 100 is a controlling lever 16. This lever is provided with a rearwardly projecting arm 17 which is connected to the arm 3 on the body by means of the pivot 18 which engages the longitudinal slot 19 in the arm on the body. 105 Thus arranged, when one end of the lever is pushed forward, the front ends of the runners and the pivoted rave sections are swung laterally in the opposite direction.

The lever projects at each side of the 110

raves to form foot rests and is provided with holes 19' for the attachment of a rope so that the sled may be steered by the hands as well as by the feet or the lever may be 5 conveniently grasped by the hands of the coaster lying face down on the sled. The pivoting of the raves permits free flexing of the runners and at the same time, the runners are well supported.

10 The first rigid knee,—that is, the first knee rigidly secured to the body, is preferably somewhat flexible, thereby relieving the runners of strain and at the same time effectively supporting them as stated.

15 In the modification shown in Fig. X, my improvements are adapted to a two-knee structure and each rave has only two sections. The swinging knee is not present in this structure. The structure is very satisfactory in light sleds, but is not quite as strong or as flexible in sleds of the same weight of material as the three-knee structure shown in Fig. I.

20 I have illustrated and described my improvements in simple and very practical embodiments thereof.

I am aware that modifications other than the one illustrated are possible without departing from my invention, but I believe the 30 disclosure made will enable those skilled in the art to which this invention relates to embody the same as may be deemed desirable, and therefore have not attempted to illustrate or describe such further modifications herein.

35 Having thus described my invention, what I claim as new and desire to secure by Letters Patent is:

1. In a steering sled, the combination of 40 the flexible runners, a body, a plurality of knees to which the runners are secured, the front knee being slidably associated with the body, the other knees being rigidly secured thereto, the side members of the front 45 rigidly secured knee being flexible, raves consisting of a plurality of sections, the rear sections being rigidly secured to the knees which are rigidly secured to the body with their front ends projecting beyond the front 50 rigidly secured knee, the rear ends of the intermediate rave sections being pivoted to the forwardly projecting ends of the rear rave

sections, their front ends being rigidly secured to the front movable knee with their front ends projecting forwardly beyond the 55 same, the rear ends of the front rave sections being pivotally secured to the forwardly projecting ends of the intermediate rave sections and rigidly secured to the front ends of the runners, a cross bar connecting 60 the front ends of the runners, and means for swinging the front ends of the runners and the pivoted rave sections laterally, all coacting for the purpose specified.

2. In a steering sled, the combination of 65 the flexible runners, a body, a plurality of knees to which the runners are secured, the front knee being slidably associated with the body, the other knees being rigidly secured thereto, raves consisting of a plurality of 70 sections, connected by vertical pivots, the pivots being disposed in front of but adjacent to the said front movable knee and the said rigidly secured knee at the rear thereof, the forward ends of the front rave sections being secured to the forward ends of the 75 runners, a cross bar connecting the forward ends of the runners and raves, and means for swinging the front ends of the runners and the pivoted rave sections laterally, all coacting for the purpose specified.

3. In a steering sled, the combination of 80 the flexible runners, a body, a plurality of knees to which the runners are rigidly secured to the body, the side members of 85 the front rigidly secured knee being flexible, raves consisting of a plurality of pivoted sections, the pivots being vertically disposed in front of but adjacent to the front rigidly secured knee, the forward ends 90 of the front rave sections being connected to the forward ends of the runners, a cross bar connecting the forward ends of the runners and raves, and means for swinging the front ends of the runners and the pivoted 95 rave sections laterally, all coacting for the purpose specified.

In witness whereof, I have hereunto set my hand and seal in the presence of two witnesses.

ADELBERT C. HIMEBAUGH. [L. s.]
